United States Patent Office.

GEORGE SHARP, OF PHILADELPHIA, PENNSYLVANIA.

Design No. 4,715, dated March 14, 1871.

DESIGN FOR A SPOON OR FORK HANDLE.

The Schedule referred to in these Letters Patent and making part of the same.

I, GEORGE SHARP, of the city of Philadelphia, in the State of Pennsylvania, have invented and produced a new and original Design for the Handles of Forks, Spoons, and other similar articles of table use, of which the following is a specification.

The nature and object of my design are fully represented in the accompanying photographic illustrations, figs. 1 and 2, to which reference is made.

Figure 1 represents the upper side of a table fork, and

Figure 2, the under side of the same, and the contour or profile of the sides or edges, and the end of the handle.

A B, the ornamental configurations on the upper surface, see fig. 1, and the ornamental configurations on the under surface, see fig. 2, represent respectively my said design.

Claim.

I claim as my invention—

1. The contour or profile of the side and end edges of the handle A B, substantially as shown.
2. In combination with the said contour or profile of the side and end edges of the handle A B, the ornamental configurations on the upper surface of the same, substantially as shown in fig. 1.
3. In combination with the said contour or profile of the side and end edges of the handle A B, the ornamental configurations on the under surface of the same, substantially as shown in fig. 2.

GEORGE SHARP.
